UNITED STATES PATENT OFFICE

RUDOLPH W. SCHROEDER, OF GLENVIEW, ILLINOIS

AEROPLANE PROPELLER

Application filed August 2, 1930. Serial No. 472,615.

This invention relates to aeroplane propellers in which the pitch of the blades may be varied to suit various requirements.

When an aeroplane is at rest and it is desired to take-off with that aeroplane, it requires a considerable amount of power to get the aeroplane into motion and into the air. Therefore, when the aeroplane is rising on the take-off a low pitch for the propeller blades is desirable. This low pitch is also very desirable for climbing after the machine is in the air, but for rapid flight in a substantially horizontal direction, or in a downward direction, a high pitch is found to be desirable.

One object of my invention therefore is to provide a propeller having blades which are angularly adjustable about an axis at substantially right angles to the axis of rotation of the propeller, since it is very desirable to have an aeroplane propeller which is so constructed that the blades thereof may be moved so as to give either a high or a low pitch thereto.

More specifically my invention contemplates the provision of means for varying the angular positions of the blades by a simple operation controlled by the pilot of the aeroplane. The pilot merely has to slow down the speed of the propeller to a predetermined speed and then increase the speed of the propeller thereafter to change the blades from one pitch to another.

In order to accomplish the rotation of the blades of the propeller about an axis perpendicular to the axis of rotation of the propeller, I prefer to employ a propeller so constructed as to be rotated by means of the centrifugal force acting on the mass of the blades as the propeller rotates.

A still further object of this invention is to provide a propeller which is very simple in design, and is more rugged than any of the devices now known to those skilled in the art to which this invention pertains.

In the drawings—

Fig. 1 represents a side view of the mechanism for rotating the blades of the propeller in one direction about their longitudinal axes and the stop mechanism for limiting the

movement of the propeller blades in the opposite direction;

Fig. 2 is a detailed view of a part of the mechanism shown in Fig. 1;

Fig. 3 is a cross-section through the hub structure of the propeller showing the manner in which the propeller blades are rotatably mounted on the hub;

Fig. 4 is a cross-section on the line 4—4 of Fig. 3;

Fig. 5 shows the equalizing yoke for the propeller blade;

Fig. 6 is a cross-section taken substantially along the line 6—6 of Fig. 1;

Figs. 7 and 8 are detailed perspective views of parts of the mechanism shown in Fig. 6;

Figs. 9, 10 and 16 are diagrammatic views showing the action which the centrifugal force has on the centers of mass of the two portions of each propeller blade which lie on opposite sides of the center of rotation of the blade;

Fig. 11 is a diagrammatic view of the propeller as the same would appear as viewed from the front of an aeroplane upon which the propeller is mounted, the stop mechanism being removed;

Fig. 12 shows the position of one of the propeller blades and the stop mechanism when the propeller is being used for traveling at high speeds;

Fig. 13 shows the position of the same propeller blade as shown in Fig. 12 when the propeller is being used for climbing or taking off;

Fig. 14 illustrates the position to which the blade is moved when it is desired to change from a low pitch to a high pitch, or from a high pitch to a low pitch;

Fig. 15 is an enlarged top view of the device shown in Fig. 14 with the blades in a different position of adjustment.

Referring now more particularly to Fig. 3, the reference numeral 1 represents the tapered forward end of the propeller shaft of an aeroplane and 2 represents the hub portion of the propeller which is keyed to the propeller shaft by the key 3 in a well known manner. The hub portion 2 has outwardly extending stub shafts 4 formed in

tegral therewith. Each of the stub shafts 4 is provided with a bearing portion 5, and a race 6 is fitted over this bearing portion. A second race 7 is fitted within a sleeve 8 5 screw threaded into the respective propeller blade 9. Antifriction rollers 10 are interposed between the races 6 and 7 so that the propeller blade will rotate freely about the stub shaft in a direction about the longitudinal axis of the stub shaft and propeller blade. Similarly the outer end of each of the stub shafts is provided with a bearing portion 11 about which is fitted a race 12, a second race 13 being fitted within the bearing surface 14 on the interior of the propeller blade. Antifriction rollers 15 are interposed between the races 12 and 13, and assist the antifriction rollers 10 to provide relatively free rotation for the propeller blades 10 about the axis of the stub shaft.

Due to the high speed at which the propeller is required to rotate centrifugal force tends to move the propeller blade outwardly in a direction along the longitudinal axis of 25 the stub shaft, and therefore it is necessary to prevent this by suitable means. I therefore provide each of the stub shafts with a screw threaded portion 16 upon which I thread the collar or thrust bearing 17, this 30 thrust bearing being held in place by means of a lock nut 18 and a lock washer 19, the lock nut being screw threaded on a portion of the stub shaft which is slightly smaller in diameter than the portion upon which 35 the thrust bearing is screw threaded. I interpose a suitable antifriction bearing between the thrust bearing 17 and the enlarged end 20 of the sleeve 8. This comprises the races 21 and 22 and antifriction rollers 23, 40 the latter being interposed between the races as is clearly illustrated in Fig. 3.

With the construction just referred to, it will be seen that while the propeller blades are free to rotate about the axes of the stub 45 shafts 4, they are not permitted to have any movement in a direction longitudinally of the said axes.

In the preferred form of my invention I employ spring means for normally holding 50 the blades of the propeller at a relatively high pitch, and I will now proceed to describe this means and the means for equalizing the movement of the propeller blades so that one propeller blade will not rotate to a 55 different angle of pitch than the other propeller blade.

Referring more particularly to Figs. 1, 3 and 6, it will be seen that the hub 2 has a screw threaded portion 24 at the forward end 50 thereof and upon this I screw the nut 25 which fits within a suitably formed recess in the forward end of the hub 2 as best seen in Fig. 3. This nut 25 has an enlarged head 26 at its inner end and a second nut 27 screw 55 threaded at 28 to the hub portion has the

inner end thereof adapted to engage and bear against the enlarged head of the nut 25, thus preventing the nut 25 from working loose and preventing the propeller from slipping off the propeller shaft 1.

On the forward end of the hub 2, I screw 70 thread a collar 29, this collar having the integrally formed outstanding ears 30 reinforced by ribs 31. A shaft 32 as best seen in Fig. 6 passes through the ears 30 and is provided with nuts 33, which are threaded on opposite ends of the shaft to prevent longitudinal movement thereof, and these nuts are held in place by the cotter pins 34 or equivalent fastening means.

Mounted on the shaft 32 is a drum comprising the outer cylindrical member 35 and the side walls 36. On the exterior surface of each of the side walls 36 I provide brackets 37 and these brackets are connected by means of a stud bolt 37' held in place by means of the nuts 38 screw threaded on each end of the bolt 37'. A coiled spring 39 has the coils thereof wrapped about the cylindrical surface 35 of the drum and each end of the coiled spring is provided with an eyelet 40 for a purpose which will appear later. The ends of the coils are arranged between the bolt 37' and the cylindrical surface of the drum 35 and the bolt 37' therefore maintains a predetermined amount of tension in the coiled spring.

On the outer surface of each propeller blade adjacent the hub of the propeller, I provide 100 a split collar 41, and this split collar has lugs 42 and 43 thereon adjacent the split portion of the collar. A bolt 44 provided with a nut 45 is used to hold the ends of the split collar together, and to clamp the split collar tightly in place on the propeller blade. The collar 43 is provided with an outstanding integral bracket 46 having an opening 47 therein.

In the eyelets 40, in each end of the spring 110 39, I arrange a bolt 48. This bolt also passes through a swivel 49, and the bolt is held in place by a nut 50. The clevis 49 is free to rotate about the bolt 48. A metal strap or wire 51 is connected to the bracket 46 and also to the swivel 49 it being understood that the swivel 49 has an opening therethrough through which the looped portion 52 of the strap may extend, the other end of the strap passing through the opening 47 in the U-shaped bracket 46. Thus it will be seen that each of the straps 51 will tend to rotate its respective propeller blade about the axis of 115 said stub shaft, and this rotation is in such a direction as to move the propeller blades to a greater pitch.

From the preceding description it will be seen that the spring 39 tends to move the propeller blades in one direction, that direction being such a direction as to give to the blade 120 the maximum permitted pitch or at least a 125

greater pitch. The spring 39 is not extremely strong, but is sufficiently so as to move the blades of the propeller in the directions indicated when the propeller is stationary or rotating at a relatively slow speed. In order to move the propeller blades in the opposite direction, I avail myself of the centrifugal force which acts on the centers of mass of the parts of the propeller blades which lie on opposite sides of the centers of rotation thereof.

The propeller blades are provided with leading edges 53 and trailing edges 54. The blades rotate about the axes indicated by the center lines 55. The centers of mass 56, 56b, 56c, and 56d lie on opposite sides of the center lines 55. These centers of mass rotate in planes, such as 59 having a fixed perpendicular distance Z to axis 57 and perpendicular to center line 59. I will now describe the action of the centers of mass under the action of centrifugal force developed during the rotation of the propellers.

Figure 9 shows the position of the center of mass 56 when the propeller is at rest and under the influence of the spring 39. 57 represents the axis of rotation of the blades and 58 the plane of rotation of center line 59. The center of mass is outside of plane 58, see Figures 9, 10, and 11, and as the propeller rotates, tends to seek a position as remote from the axis 57 as is possible. The extreme position would be in the plane of rotation 58. In the present instance however, I have shown an intermediate position 56a. X and X' indicate the distances between the center of mass when at 56 and 56a respectively and the plane 58. Y and Y' similarly represent the distances to the plane through 57 and 59. W and W' indicate the straight line distances to the center of mass when at 56 and 56a respectively.

It is obvious that the value W' is greater than W so that it is readily appreciated that the center of mass will move from 56 to 56a instead of in the opposite direction, for when moving in the opposite direction W will decrease. The theoretical arm a which carries the center of mass will, therefore, move to position a'. Since a represents somewhat the actual pitch angle of the blade, it will be seen that the pitch of the blade is decreased as the centrifugal force increases. The position of arm a does not actually represent the pitch angle of the blade, but the arm a does bear a fixed relation to the pitch angle of the blade.

In Fig. 16 I have indicated in dotted lines the position of the center of mass 56b which, as will be seen from Fig. 11, lies on the opposite side of the center line 55. The tendency is for the center 56b when acted upon by centrifugal force to also move towards the plane of rotation 58 and of course since this movement tends to rotate the blade 9 as a

whole in the same direction as the center of mass 56, the two forces unite to rotate the blade and do not oppose each other.

There are therefore two forces tending to rotate the blades of the propeller when the propeller is rotating. One of these forces is the spring which tends to rotate the propeller blades from a low pitch to a high pitch and the other is the centrifugal force which tends to rotate the propeller blades from a high pitch to a low pitch. When the propeller is rotating at a relatively slow speed, the force of the spring is sufficient to overcome the centrifugal force at that speed and consequently the blades are moved to a high pitch. If the speed of the propeller, however, is increased to a maximum speed, or the speed which is desired for propelling the aeroplane, the centrifugal force increases to such an extent that it overcomes the action of the spring 39 as well as the friction which occurs in the thrust bearing which comprises the races 21 and 22 and antifriction rollers 23. The centrifugal force therefore rotates the blades from a high pitch to a low pitch, or at least a lower pitch than the blades normally occupy when the propeller is at rest or moving at a relatively slow speed.

I now wish to describe the mechanism whereby I govern the pitch to which the blades are moved under the action of centrifugal force. This means comprises a stop member for limiting the rotation of the blades in that direction which causes the pitch to decrease. This stop may have any number of selected stop projections thereon so as to enable one to select any one of a number of pitches to which the blade may be moved under the action of centrifugal force. Preferably however, I provide a stop member having only two surfaces which I shall denote cam surfaces and against which a stop carried by the blade is adapted to abut. I also provide mechanism for selecting the particular cam surface against which the stop is to abut. Any unbalancing, which may be occasioned by the off-center location of the stop mechanism and selector mechanism, may be rectified by applying weights equivalent to the unbalanced weight of said mechanisms on the opposite sides and at a proper distance from the axis of rotation of the propeller system.

The hub 2 is flattened on two opposite sides as at 60, and adjacent these flattened portions are flanges 61 which are integral with the hub and form bearings for the rings 62. These rings 62 are substantially of the same thickness as the flanges 61, and the flat faces of the rings 62 are substantially flush with the flat faces on the flanges 61. Each of the rings 62 and flanges 61 have co-operating flat surfaces abutting against each other as at 63 so as to prevent the ring from rotating relatively to the flange 61. The flange 61

has a bearing member 64 secured thereto by any suitable fastening means such as the rivet 65, and on this bearing member 64 I provide a pivot 66 adapted to rotatably support the cam member 67, the detent member 68 and the ratchet member 69, these members being fastened rigidly to each other, or formed from a single piece of material if so desired. The bearing member 64 is also secured to the ring 62 by means of a pivot 70, which passes through the bearing member 64, and the ring 62. In other words, the ring 62 merely performs the function of a bearing surface upon which the bearing member 64 10 may be secured and the device would operate equally as well if the ring 62 were formed as an extension of the flange 61. For the purposes of construction however, it is preferred to have the ring 62 and the flange 61 separate 15 members.

The pivot 70 also carries a detent member 71 which has a pointed end 72 adapted to be received within the notches 73 of the detent member 68. A spring 74 secured to an arm 25 of the detent member 71 abuts against the upper surface of the bearing member 64 and the ring 62, and tends to rotate the detent member 74 in a counter-clockwise direction as viewed in Fig. 6, the surfaces of the ring 30 62 and member 64 being substantially flush at this point. Since the pivot 66 and the pivot 70 are both carried by the member 64 which in turn is rigid with the hub portion, the detent member 71 will always tend to 35 hold the detent member 68 and consequently the cam 67 in any position of adjustment to which the same may be moved by a mechanism which I shall now describe.

The split collars 41 each carry a roller 76 40 mounted on a pivot 77, screw threaded as at 78 (see Fig. 3) to the split collars 41. A yoke member 79 has an opening 80 therein which is rotatably mounted on a bearing portion 80 of the hub 2 as best illustrated in Figs. 45 3 and 6. This yoke 79 has notches 81' in opposite ends of the flange 82' which forms a part of the yoke and the rollers 76 are adapted to be received within said notches. The spring 39 tends to rotate the propeller blades 50 in opposite directions, and of course, the centrifugal force also acts to rotate the propeller blades in opposite directions. Regardless of whether it is the spring or the centrifugal force which is acting on the propeller 55 blades to rotate the same, the yoke 79 will tend to equalize the amount of movement imparted to the propeller blades. In other words, one of the propeller blades cannot have a different pitch than the other propeller 60 blade. I do not however, wish to limit myself to this particular means of equalizing the movements of the blades although it will be readily seen that the means which I employ is very simple and yet very efficient.

65 I also secure to each of the collars 41 a stop

member 81 which is dove-tailed as at 82 (see Fig. 6) to the split collar and held in place by means of the rivets 83 or the like. If desired the stop member 81 may be made as an integral part of the split ring. On the 70 end of the stop member 81, I pivot a pawl 84 at 85. This pawl 84 has a tooth 86 at the end thereof adapted to engage the teeth 87 on the ratchet member 69. A spring 88 is secured to the pawl 84, and is yieldingly urged 75 against the flat surface 60.

I will now proceed to describe the operation of the stop mechanism under the action of the centrifugal force, and also under the action of the spring 39. The collar 41 of course, is carried by the rotatable blade of the propeller and the ratchet wheel 69, detent member 68 and cam member 67 are all carried rigidly on the hub structure. The pawl 84 is carried by the stop member 81 and of course will move with the stop member 81 and the collar 41. Therefore, in Fig. 6, if the collar 41 is rotated in a clockwise direction, the pawl will be carried therewith in the same direction and this will cause the tooth 86 to engage the adjacent tooth 87 of the ratchet member 79 and rotate the cam member 67 from the position shown in that figure to the position shown in Fig. 13. This brings the low cam surface 89 into a position such that when the collar 41 is rotated in a counter-clockwise direction as viewed in Fig. 6, the stop 81 will abut against this low cam surface instead of the high cam surface 90 as illustrated in Fig. 6, and also in Fig. 13. Similarly when the 90 collar 41 is again rotated in a clockwise direction, the pawl again moves the cam member in a counter-clockwise direction and thus 95 positions the next high cam surface 90 in a position to be engaged by the stop 81 when the collar 41 is again rotated back to the position shown in Fig. 6, or in Fig. 12. In other words, each complete movement of the collar 41 in a clockwise direction and then in a counter-clockwise direction brings the next succeeding cam surface on the cam member 67 100 into position to be engaged by the stop 81.

In the form of the invention which I have shown in the drawings, I have provided six cam surfaces on the member 67, there being three cam surfaces 89 and three cam surfaces 90. It is possible to have my device operate with only two cam surfaces spaced about the periphery of the cam 67, but by providing six cam surfaces, or three pair of cam surfaces, it is not necessary to rotate the cam through as great an angle for each movement of the collar 41. Or I may provide more cam surfaces, for instance, four pairs of surfaces such as 89 and 90, and I may also provide in addition to cam surfaces such as 89 and 90, additional cam surfaces which will permit greater or less movement of the collar 41 in a direction 110 toward the cam member 67.

115 It will be noted that the movement of the 120

collar 41 in Fig. 6 in a counter-clockwise direction moves the blade 9 also in a counter-clockwise direction so as to decrease the angle of pitch which is the angle which the blade makes with the plane of rotation 58. 5 Therefore, when the stop 81 is against the high cam surface 90, the blade 9 is at a greater pitch than when the stop 81 is against the cam surface 89. As stated before, the spring 10 39 has the tendency to rotate the collar 41 in a direction to move the blades to its maximum permitted pitch and this would be in a clockwise direction as viewed in Fig. 6. A stop 91 on the ring 62 abuts against the stop 15 81 and limits the amount of rotation which may be given to the blade 9 in a clockwise direction. This position of the blade is illustrated in Fig. 14, and it will be noted that the pitch of the blade is greater than in either 20 Figs. 12 or 13.

Furthermore, according to the previous description, it will be noted that the centrifugal force is the force which tends to rotate the propeller blade to decrease the pitch thereof and this force will act to rotate the 25 collar 41 and sleeve 9 in a counter-clockwise direction as viewed in Figs. 12, 13 and 14. This centrifugal force overcomes the force of the spring when the propeller is rotating at high speeds and therefore when the propeller is rotating at high speeds, the stop 81 is always rotated against the cam surface which happens to be in operative position, and it will be noted that each successive 30 movement of the stop member 81 to the right as viewed in Fig. 6 and then to the left will cause the stop member 81 to engage first the cam surface 90 and then the cam surface 89 and so on.

Let us now assume that the propeller which has been described is mounted on the propeller shaft of an aeroplane and the plane is on the ground ready to take-off. Before the engine is started the blades 9 are at a high pitch because of the fact that the same are under the influence of the spring 39. After the motor has been started and the propeller is rotating at a relatively slow speed, the propeller blades are still in the position 45 shown in Fig. 14, that is, they are at a high pitch. As the speed of the motor is increased, however, to permit the aeroplane to take-off, the centrifugal force becomes greater and greater and gradually overcomes the action 50 of the spring 39. It is assumed that the cam is now in the position shown in Fig. 13 and not as shown in Fig. 6 or 12. Therefore, as the centrifugal action moves the propeller blade in a counter-clockwise direction as in 55 Fig. 13, the stop 81 moves closer and closer to the cam surface 89 and finally engages said cam surface, arresting any further movement of the propeller blade in a counter-clockwise direction. The propeller blade 60 being at a low pitch, is suitable for the pur-

poses of take-off as the low pitch gives a very great amount of power in substantially the same manner as the low pitch of a screw thread gives a greater lifting power to a screw jack or other similar mechanical device. After the aeroplane is in the air and it is desired to travel at a high rate of speed, the pilot slows down the speed of his engine momentarily, and this permits the spring 39 to act again as soon as the centrifugal force 70 has been decreased the proper amount. This causes the propeller blade to again move to the position 14, and the pawl 84 will rotate the cam member 67 until the high portion 75 90 of the cam is in the position shown in Figs. 6, 12 and 14. The pilot thereafter opens the throttle and increases the speed of the engine causing the centrifugal force to again throw the propeller blade to its minimum permitted pitch which this time is 80 greater than the pitch shown in Fig. 13, for the reason that the cam surface 90 is higher than the cam surface 89, and therefore arrests the movement of the stop 81 sooner than does the cam surface 89. This pitch of 90 the propeller is preferred for high speeds.

If the pilot should desire to climb to high altitudes while in the air, all that is necessary is to throttle the engine and then again open the throttle. The slowing down of the 95 engine will cause the cam 67 to move to the position shown in Fig. 13 and the speeding up of the engine will thereafter bring the stop 81 against the cam surface 89.

Obviously if one desired another speed or another tractive effort for the propeller blade, it would only be necessary to provide another cam surface. Also for different types of aeroplanes the same propeller could be used with a different stop member 67, 100 which stop member could be provided with cam surfaces at such distances from the center of rotation thereof as would suit the needs of that particular aeroplane, so that the best possible angles desired for the blades 105 when taking-off and driving at high speed 110 may be given to the propeller when used in any particular machine.

The air pressure may possibly have some 115 action on the blades to tend to rotate them into the plane of rotation but it is believed that centrifugal force is by far the greater force and would cause the blades to operate as described even if the propeller were rotated in a vacuum.

While I have described the action of centrifugal force on the centers of mass it will be understood that one could consider each individual particle of the mass of the blades 120 separately and the conclusions reached would 125 be the same.

Obviously a great many changes may be made in the particular construction of the propeller which I have described and shown in the accompanying drawings without de- 130

parting from the spirit of the invention or the scope of the appended claims and therefore I do not wish to limit my invention to the particular details shown in the embodiment disclosed in this application.

Having thus fully described my invention, what I desire to secure by Letters Patent of the United States is:—

1. An aeroplane propeller comprising a plurality of blades rotatably mounted on a hub portion so as to rotate about axes at substantial angles to the axis of rotation of said hub, said propeller blades being held against bodily movement away from said hub and being rotatable about their own axes by centrifugal force exerted on the mass of the propeller blades in a direction to decrease the pitch thereof, and stops movable selectively to operative positions by the speed of rotation of said propeller for limiting the movements of said blades under the action of centrifugal force to thereby predetermine the pitch which is to be given to the propeller blades.
2. An aeroplane propeller comprising a plurality of blades rotatably mounted on a hub portion so as to rotate about axes at substantial angles to the axis of rotation of said hub, said propeller blades being held against bodily movement away from said hub and being rotatable about their own axes by centrifugal force exerted on the mass of the propeller blades in a direction to decrease the pitch thereof, and an adjustable stop for limiting the movements of said blades under the action of centrifugal force to thereby predetermine the pitch which is to be given to the propeller blades, said stop being controlled by the rotative speed of said propeller to selectively vary the limit of movement of the blades under centrifugal force.
3. An aeroplane propeller comprising a plurality of blades rotatably mounted on a hub portion so as to rotate about axes at substantial angles to the axis of rotation of said hub, said propeller blades being rotatable about their own axes by centrifugal force exerted on the mass of the propeller blades in a direction to decrease the pitch thereof, and stops for limiting the movements of said blades under the action of centrifugal force to thereby predetermine the pitch which is to be given to the propeller blades, said stops being selectively movable to operative positions and controlled by the speed of rotation of said propeller.
4. An aeroplane propeller comprising a plurality of blades rotatably mounted on a hub portion so as to rotate about axes at substantial angles to the axis of rotation of said hub, said propeller blades being held against bodily movement away from said hub and being rotatable about their own axes by centrifugal force exerted on the mass of the

propeller blades in a direction to decrease the pitch thereof, and stops for limiting the movements of said blades under the action of centrifugal force to thereby predetermine the pitch which is to be given to the propeller blades, said stops being adjustable to selectively vary the limit of movement of the blades under centrifugal force and selectively rendered operative by varying the speed of rotation of said propeller.

5. In an aeroplane propeller the combination with a rotatable hub member, of a blade member rotatably mounted on said hub member and held against bodily movement away from said hub member, a stop mounted on one of said members adapted to engage an adjustable stop on the other of said members to limit the rotative movement of said blade member in one direction, the adjustment of said stop being controlled by the speed of rotation of said propeller and a third stop for limiting movement of said blade member in the other direction, said blade member having means for rotating the same about its own axis in one direction and being movable in the other direction by the centrifugal force which acts on the mass of said blade member.

6. In an aeroplane propeller the combination with a rotatable hub member, of a blade member rotatably mounted on said hub member and held against bodily movement away from said hub member, a stop mounted on one of said members adapted to engage an adjustable stop on the other of said members to limit the rotative movement of said blade member in one direction, and a third stop for limiting movement of said blade member in the other direction, said blade member having means for rotating the same about its own axis in one direction and being movable in the other direction by the centrifugal force which acts on the mass of said blade member, said adjustable stop being for the purpose of varying the angle to which the blade may be moved about its own axis in one direction and being controlled by interconnecting means between said blade and said adjustable stop, operable to adjust said stop during movement of the said blade about its axis.

7. In an aeroplane propeller the combination with a rotatable hub member, of a blade rotatably mounted on said hub member, a stop mounted on said hub member adapted to engage a stop on said blade, one of said stops comprising a member having a plurality of projections thereon which may be selectively positioned to engage the other of said stop members to limit the rotative movement of said blade and determine the angle to which said blade may be rotated in one direction, said blade being rotatable in a direction to bring said stops in engagement with each other by the centrifugal force acting on the mass of said blade and being rotatable so as to move said stops away from each other

by means other than centrifugal force, said last mentioned means acting to move said blade in the last mentioned direction when the centrifugal force has been decreased to a 5 predetermined amount.

8. In an aeroplane propeller the combination with a rotatable hub member, of a blade rotatably mounted on said hub member, a stop mounted on said hub member adapted to 10 engage a stop on said blade, one of said stops comprising a member having a plurality of projections thereon which may be selectively positioned to engage the other of said stop members to limit the rotative movement of 15 said blade and determine the angle to which said blade may be rotated in one direction said blade being rotatable in a direction to bring said stops in engagement with each other by the centrifugal force acting on the 20 mass of said blade and being rotatable so as to move said stops away from each other by means other than centrifugal force, said last mentioned means acting to move said blade in the last mentioned direction when the 25 centrifugal force has been decreased to a predetermined amount, said stop which has the plurality of projections thereon being selectively movable by the pilot to selectively position the desired one of the projections in a 30 position to engage the other of said stop members.

9. A propeller for aeroplanes comprising a hub portion, blades rotatably mounted on said hub portion so as to be capable of movement from a low pitch to a high pitch and from a high pitch to a low pitch, means for moving said blades to a high pitch, means for moving said blades to a low pitch selectively operable by the pilot of an aeroplane in 35 which said propeller is adapted to be installed, a stop on said hub, a second stop on one of said blades, one of said stops having a plurality of abutments thereon adapted to engage the other of said stops to selectively arrest 40 rotative movement of said blades when the stops come into engagement with each other, and means for selectively moving said stop with the plurality of abutments to position the desired abutment in position to engage 45 the other of said stops as said stops move away from each other.

10. An aeroplane propeller comprising a hub portion adapted to be secured to the propeller shaft of an aeroplane engine, rotatable stop members on said hub portion, rotatable blades on said hub portion held against bodily movement away from said hub portion and rotatable in one direction about their own axes by the action of centrifugal force 55 acting on their masses, a spring for rotating said blades in the opposite direction, a pair of stops on said hub, a stop on each of said blades co-operating with one of said pair of stops on said hub thereby forming two pairs 60 of co-operating stops, each pair comprising

a stop on the hub and a stop on the blade, one stop of each of said pair of stops being adjustable and having a plurality of abutments thereon adapted to be arranged selectively in a position to engage the other of the stops 70 of each of said pair of stops to thereby limit the angular movement of said blade selectively at the will of the pilot of the aeroplane in which said propeller is installed, said co-operating stops on said blades and hub being 75 movable into engagement with each other by centrifugal force acting on the masses of said blades and being movable out of engagement with each other by said springs.

11. In an aeroplane propeller comprising a hub, propeller blades rotatably mounted on said hub, an equalizing member for equalizing the movement of said blades about their axes, means for holding said blades against bodily movement away from said hub, a fixed stop on each of said blades, a co-operating adjustable stop on said hub for each stop on said blades and for co-operating with the stops on said blades to limit rotative movement of said blades in one direction, 80 said adjustable stops having a plurality of abutment surfaces thereon, each of which is adapted to be positioned selectively to engage the adjacent stop on the adjacent blade, a spring for moving said blade so that the 85 stops are out of engagement with each other where the propeller is rotating at less than a predetermined speed, pawl and ratchet mechanism for moving said adjustable stops to position the desired abutments on said 90 adjustable stops in a position to engage the stops on said blade as said stops move away from each other, and means for holding said adjustable stops in desired adjusted position, 95 said propeller blades being rotatable against the action of said spring into such a position that the stops on said blades engage their co-operating adjustable stops on said hub by the centrifugal force acting on the mass of said blades after the propeller is rotated at a 100 speed higher than a predetermined amount.

12. A propeller blade as claimed in claim 11 in which the propeller blades are acted upon by a spring so as to be moved to the maximum permitted pitch and in which the hub is provided with a second stop for limiting the movement of said blade under the action of said spring.

13. An aeroplane propeller comprising a hub, stub shafts mounted on said hub, propeller blades rotatably mounted by means of suitable antifriction bearings on said stub shafts, said antifriction bearings comprising bearings for assisting rotative movement about said stub shaft and for minimizing the 120 friction caused by centrifugal force in a direction longitudinally of said stub shafts, flanges on said hub adjacent said propeller blades, collars on said propeller blades adjacent said flanges, a stop on each of said col- 125 130

lars, a pair of stops on each of said flanges adjacent said collars and arranged to abut the stops on the respective collars when the propeller blades are moved in opposite directions, one of said stops on each of said flanges comprising a rotatable member having different portions of the periphery thereof at different radial distances from the center of rotation thereof, pawl and ratchet mechanism for rotating said last mentioned stop to selectively position the desired portion of the periphery of said last mentioned stop in a position to engage the respective stop on said collars while the stops on said collars and said rotatable stop members are out of engagement with each other, thereby limiting the rotative movement of said blades in one direction a predetermined amount which may be selected upon proper rotation of said rotatable stop member, means for controlling the rotation of said rotatable stop member, and a spring arranged symmetrically with respect to said hub portion and being operable to rotate both of said blades to a position such that the stops on said collars are out of engagement with said rotatable stops, each of said stops on said flanges other than said rotatable stops being for the purpose of limiting the rotative movement of said blades under the action of said spring, said blades being rotatable in a direction opposite to that in which they are moved by said spring by the centrifugal force which acts upon the mass of said blades, said stops on said collars and said rotatable stops co-operating to form the limiting means for the rotative movement of said blades under the action of centrifugal force.

14. An aeroplane propeller comprising a hub, stub shafts mounted on said hub, propeller blades rotatably mounted by means of suitable antifriction bearings on said stub shaft, said antifriction bearings comprising bearings for assisting rotative movement about said stub shaft and for minimizing the friction caused by centrifugal force in a direction longitudinally of said stub shafts, flanges on said hub adjacent said propeller blades, collars on said propeller blades adjacent said flanges, a stop on each of said collars, a pair of stops on each of said flanges adjacent said collars and arranged to abut the stop on the respective collars when the propeller blades are moved in opposite directions, one of said stops on each of said flanges comprising a rotatable member having different portions of the periphery thereof at different radial distances from the center of rotation thereof, pawl and ratchet mechanism for rotating said last mentioned stop to selectively position the desired portion of the periphery of said last mentioned stop in a position to engage the respective stop on said collars while the stops on said collars and said rotatable stop members are out of en-

gagement with each other thereby limiting the rotative movement of said blades in one direction a predetermined amount which may be selected upon proper rotation of said rotatable stop member, means for controlling the rotation of said rotatable stop member, a spring arranged symmetrically with respect to said hub portion and being operable to rotate both of said blades to a position such that the stops on said collars are out of engagement with said rotatable stops, each of said stops on said flanges other than said rotatable stops being for the purpose of limiting the rotative movement of said blades under the action of said spring, said blades being rotatable in a direction opposite to that in which they are moved by said spring by the centrifugal force which acts upon the mass of said blades, said stops on said collars and said rotatable stops co-operating to form the limiting means for the rotative movement of said blades under the action of centrifugal force, said blades being held against bodily movement away from said hub and equalizing means for equalizing the rotative movement of said blades about their axes comprising a member rotatable about an axis concentric with said hub and having means interlocking with fixed means on each of said blades.

15. An aeroplane propeller comprising a plurality of blades, a hub, spindles extending at substantial angles to said hub upon which said blades are rotatably mounted, said propeller blades being held against bodily movement away from said hub and being rotatable about their respective spindles by centrifugal force exerted on the mass of the propeller blades in a direction to decrease the pitch thereof, a plurality of stops selectively movable to operative positions for limiting the movements of said blades under the action of centrifugal force to thereby predetermine the pitch which is to be given to the propeller blades when said propeller blades are moved against said stops by the action of centrifugal force, and means for selectively moving the stops to operative positions to limit the movement of the blades, said last mentioned means being operable by means on said blades when said blades move to a position away from said stops.

16. In an aeroplane propeller the combination with a hub portion, spindles extending outwardly from said hub portion, blades rotatably mounted on said hub portion, adjustable stops mounted on said hub portion, a cooperating stop on each of said blades adapted to cooperate selectively with one of the stops on said hub portion, said blades being rotatable about said spindles to bring said stops on said blades into engagement with the selected stops on said hub portion when said propeller rotates and said blades move about their spindles under the action of

- centrifugal force acting on the masses of the blades, means acting in opposition to the centrifugal force for rotating said blades about their respective spindles in a direction to move the stops on said blades and the selected stops on said hub portion away from each other when the centrifugal force tending to rotate the blades becomes less than the means for rotating the blades in a direction opposite to that in which the blades are rotated by centrifugal force, and means operable by said blades as they rotate in a direction to move said stops out of engagement with each other for selectively positioning the stops on said hub portion which are to be engaged by the stops on said blades when said blades again move about their respective spindles under the action of centrifugal force.
17. An aeroplane propeller comprising a hub, blades rotatably mounted on said hub, said blades being rotatable about their axes under the action of centrifugal force acting on the mass of said blades when said blades rotate, a plurality of stops on said hub, a stop on each of said blades adapted to abut against a selected one of said stops on said hub to limit the movement of said blades under the action of centrifugal force to thereby determine the angle to which each of the blades moves, and means controlled by the speed of rotation of said hub for selecting the stops on said hub which are adapted to limit the movement of said blades about their respective axes, different stops on said hub being adapted to limit the rotative movement of said blades at different positions in their paths of rotation.
18. A propeller comprising a hub, an adjustable stop on said hub, a blade rotatably mounted on said hub, a cooperating stop on said blade, means for moving said last mentioned stop away from said adjustable stop when said hub is rotating at a relatively slow speed and when said hub is not rotating, said blade being rotatable to bring the stop thereon into engagement with the cooperating stop on said hub when said hub rotates at relatively high speeds due to the centrifugal force acting on the mass of said blades, and means operable when said stop on said blade moves away from said adjustable stop for adjusting said stop so that when said blade again moves under the action of centrifugal force to bring said stops into engagement with each other, said blade will have a different limiting position than on the previous movement of said blade under the action of centrifugal force.
19. An aeroplane propeller comprising a plurality of blades rotatably mounted on a hub portion to rotate about axes at substantial angles to the axis of rotation of said hub portion, said propeller blades being held against bodily movement away from said hub portion and being rotatable about their own axes by centrifugal force exerted on the masses of propeller blades in a direction to change the pitch thereof and stops movable selectively to operative positions by the speed of rotation of said propeller for limiting the movements of said blades under the action of centrifugal force to thereby predetermine the pitch to which said blades may move under the action of centrifugal force.
20. A device as claimed in claim 19, in which the movement of the blades about their axes in a direction opposite to the direction in which they move under centrifugal force causes the operation of selecting mechanism for selecting the stop next to be positioned in operative position to limit the movements of said blades under the action of centrifugal force when said blades next move under the action of centrifugal force.
- In testimony whereof I have signed my name to this specification on this 20th day of July, A. D. 1930.
- RUDOLPH W. SCHROEDER.
